(57) CLAIM

The ornamental design for a bottle, as shown and described.

DESCRIPTION

FIG. 1 is a perspective view of the bottle showing our new design;

FIG. 2 is a front elevational view thereof, the rear, right and left side elevational views being mirror images thereof;

FIG. 3 is a top view thereof; and,

FIG. 4 is a bottom view thereof.

The broken line showing of the environment is for illustrative purposes only and forms no part of the claimed design.
